(57) **CLAIM**

The ornamental design for a trolley platform, as shown and described.

DESCRIPTION

FIG. 1 is a perspective view of the trolley platform showing my new design;

FIG. 2 is a front elevational view of the trolley platform; FIG. 3 is a rear elevational view of the trolley platform; FIG. 4 is a right side elevational view of the trolley platform; FIG. 5 is a left side elevational view of the trolley platform; FIG. 6 is a top plan view of the trolley platform; and, FIG. 7 is a bottom plan view of the trolley platform.

The broken lines in the figures are for the purpose of illustrating portions of the trolley platform that form no part of the claimed design.
